UNITED STATES PATENT OFFICE.

JOHN S. HALL, OF NEW YORK, N. Y.

OIL-CUP.

SPECIFICATION forming part of Letters Patent No. 396,336, dated January 15, 1889.

Application filed July 16, 1888. Serial No. 280,058. (No model.)

To all whom it may concern:

Be it known that I, JOHN S. HALL, a citizen of the United States, residing in the city, county, and State of New York, have invented 5 an Improvement in Oil-Cups, of which the following is a full, clear, and exact description, reference being had to the accompanying drawings, forming part of this specification.

My invention consists in the combination, 10 in an oil-cup, of a skeleton frame rigidly attached to the upper rim or mouth of the cup, and uniting the same to the central valve-tube, and a lid or cover adapted to fit over said frame and close the mouth of the cup, 15 and having a central opening adapting it to move freely vertically and to be tilted laterally on said valve-tube, as hereinafter set forth and for the purpose specified.

Figure 1 is an elevation in perspective of 20 an oil-cup containing my invention, and showing the movable cover elevated above the skeleton top. Fig. 2 is a vertical central section of the cup shown in Fig. 1, the cover being closed down upon the skeleton top. Fig. 25 3 is a plan of the skeleton top. Fig. 4 is an elevation of a modified form of cup containing my invention, and Fig. 5 is a vertical central section of the same.

In the oil-cup shown in Figs. 1 and 2 the 30 body or reservoir A is of glass. B is the shank of the cup, secured, as presently described, to an aperture, a, in the bottom of the glass body A, and serving to mount the cup upon a journal or bearing, and being hollow, 35 as shown, to permit the oil to flow through it to the bearing.

C is the valve-tube extending longitudinally of the body A and passing through the aperture a, and screw-seated at its lower end in 40 the shank B, which is interiorly threaded for this purpose. The body A is preferably furnished with an external flange, a', around the orifice a, and the upper face of the shank has a corresponding annular recess, b', provided with a packing-ring, b², against which 45 said flange a' engages, thus constituting a tight joint between the shank and the body A.

C' is the valve-stem extending longitudinally of the tube C and bearing or constituting 50 a valve, c, working to a seat in the shank B, as shown, and said stem has a threaded bearing, as shown at c', in the valve-tube, and

is furnished with the cap or head c². An orifice, c⁵, in the wall of the tube C permits the oil to pass from the body A to the valve c. 55

D is my improved top, and it is in the form of a skeleton frame, as shown, composed of the two concentric rings d and d' and the arms d², preferably three in number, uniting said rings, as shown. The external ring, d, 60 constitutes a rim adapted in diameter and outline to fit upon the rim or mouth of the body A. The ring d' constitutes a collar adapted to engage and be fixed upon the valve-tube C. In cups such as shown in Figs. 65 1 and 2, wherein the valve-tube extends longitudinally through the cup, I form a shoulder, c³, on the tube, against which the collar d' engages, as shown, or the collar may be screwed to a threaded seat on the tube. 70

E is a cover or lid adapted in diameter and outline to fit over and close down upon the skeleton top D. This cover has a central aperture, e, by which it is mounted loosely upon the upper end, c⁴, of the valve-tube, so that 75 said cover is free to move vertically on said tube, where its upward movement is limited, and its escape from the tube is then prevented by the cap of the valve-stem, while the opening e is of such diameter as to permit 80 the cover to be tilted laterally on the tube.

In putting together the several parts of the cup thus described the skeleton top D is shouldered or fixed on the valve-tube, and the valve-tube is then screwed to its seat at its 85 lower end in the shank B, the top D fitting at its rim d to and upon the rim of the body A. The body A is thus clamped longitudinally between the face of the shank B at its bottom and the rim d of the top D. When 90 the glass body A is clamped between the shank and the skeleton top, as described, the cover E may be mounted by the aperture e, as before described, on the valve-tube at c⁴, and the valve-stem then seated in the tube, 95 as shown.

In the modified form of cup shown in Figs. 4 and 5 the glass body A has a metal socket or casing, A', in which it is inclosed, and the shank B is cast upon or secured to said socket 100 at its bottom. The skeleton top D is provided with an annular rim-flange, d³, which is threaded to screw upon the threaded top of the socket, and the valve-tube C² is fixed

upon or cast integral with the top D, the extension of the tube through the cup to the shank being dispensed with. The movable cover E is mounted, as described, upon the 5 valve-tube above the skeleton top D, and the valve-stem C' extends through and has a threaded bearing in the said tube, and reaches through the body to, and its valve has bearing against, a valve-seat in the shank, as shown.

10 An annular packing, d^4 , may be interposed between the rim d of the top D and the rim of the glass body. In this form of cup, Figs. 4 and 5, the skeleton top D is held rigidly to the mouth or rim of the cup, and the cover E 15 has vertical free play above it upon the valve-tube, and is capable of being tilted laterally thereon, as heretofore described.

The advantages obtained by the described skeleton top D and movable cover E are manifest, while the cover E may be readily and 20 conveniently raised and tilted laterally at

any time to give access to the body A for the purpose of cleaning or filling the cup, and the cover being mounted loosely upon the valve-tube, it will fall to its place by gravity upon 25 the skeleton top when released.

What I claim as my invention, and desire to secure by Letters Patent, is—

In an oil-cup, the combination, with the cup A and valve-tube, of the skeleton frame D, fitted and rigidly attached to the rim of the cup and uniting the same to the valve-tube, and the lid E, adapted to close down upon and cover said frame, and provided with the aperture e, by which said cover is free to move 30 vertically and be tilted laterally upon the valve-tube, substantially as set forth.

JOHN S. HALL.
